COMBINED PEN WARMER AND ACCESSORY RACK FOR PRINTERS

Wiley Glenn Long, Sr., Newnan, Ga.

Application March 30, 1956, Serial No. 40,861

Term of patent 14 years

(Cl. D64—11)

Fig. 1 is a front elevational view of a combined pen warmer and accessory rack for printers showing my new design;

Fig. 2 is a top plan view thereof;

Fig. 3 is a side elevational view thereof as viewed from the right of Fig. 1;

Fig. 4 is a side elevational view thereof as viewed from the left of Fig. 1;

Fig. 5 is a bottom plan view; and

Fig. 6 is a rear elevational view thereof.

I claim:

The ornamental design for a combined pen warmer and accessory rack for printers, as shown.
